UNITED STATES PATENT OFFICE.

HARRY E. KHOURY, OF NEW BEDFORD, MASSACHUSETTS.

WARP STOP MOTION.

Application filed July 6, 1926. Serial No. 120,739.

The present invention relates to warp stop motions for looms, and more particularly to that type of stop motion wherein the harness or shed forming heddles perform the additional function of detector wires, and co-operate with the detector bar extending therethrough and having a detecting movement as the heddle frames are raised and lowered in the loom operation.

10 The invention relates to that type of mechanism disclosed in my Patents Nos. 1,527,195 and 1,527,196, granted February 24, 1925. These patents show a stop motion comprising a detector bar movably mounted in each 15 heddle frame, and adapted to be rocked as the frames are raised and lowered. The mechanism also embodies means upon the loom, which effects rocking of the bar and also serves to maintain a power operated 20 knock-off mechanism inoperative. The detector bar rocking means is connected with the knock-off mechanism, so that upon locking of the bar against rocking movement, the knock-off mechanism is rendered operative and the loom stopped.

25 The present invention is an improvement upon the structure disclosed in the patents referred to, and has as an object, the provision of a mechanism which is of simplified construction, and may be readily associated with a loom having any number of harnesses.

30 These and other objects of the invention, which will become clear as the description 35 proceeds, are accomplished by a mechanism, a preferred embodiment of which is illustrated in the accompanying drawings, wherein:—

Figure 1 is a side elevational view showing the mechanism removed from the loom, and associated with only such loom parts as are necessary to illustrate the operation.

Figure 2 is a view taken at right angles to Figure 1, and showing a portion of the 45 mechanism in section.

Figure 3 is a fragmentary view, showing the means for imparting a rocking movement to the detector bar as it is moved longitudinally, and

50 Figures 4 and 5 are fragmentary detail views, showing the construction of the heddles and detector bar, with the heddle illustrated as dropped in Figure 5 and locking the detector bar against movement.

55 Referring to the drawings, wherein like numerals represent corresponding parts

throughout, 10 indicates the harness or heddle frames, having therein the heddles 11, maintained in position at their upper and lower ends by guide or cross bars 12 extending therethrough. A detector bar 13 of angular cross section, which is formed by an upstanding rib 14, extends through the heddles and is movably mounted in the frame 10, it being understood that there is 60 one detector bar in each frame. The detector bar is normally arranged in each heddle, as illustrated in Figure 3, and is free to move. A feature of the present invention, which distinguishes it from those of the 65 patents referred to, is that the detector bar 13 is movable longitudinally by mechanism which will be later described, and is also rotated or rocked. As will be understood, whenever one of the warp threads breaks, its 70 heddle will drop to the position illustrated in Figure 5, wherein the rib 14 will enter the narrowed portion 11', thus locking the bar against rocking movement.

The bar has mounted thereon a collar 16, 80 fixedly held by means of a set screw 17, and this collar receives the end of a spring 18, having its other end 19 anchored in the heddle frame. The spring serves to maintain the detector bar in the position illustrated in Figure 3 with the rib 14, or, if the bar is of any other formation, with the entire bar arranged to enter the narrowed slot 11'. The position of the bar may be varied 85 by tensioning the spring 18 for adjustment of the collar 16. The means for rocking or rotating the bar as it is moved longitudinally, may take any suitable form; in the present instance, the detector bar is formed with a spiral groove 20, which receives inwardly projecting fingers 21' on the plate 21, which is secured to the frame. As the bar is pressed inwardly and longitudinally moved by the mechanism which will be described, these fingers co-operate with the 90 groove 20, and rotate the bar. Due to the fact that the plate 21 is fixed, it will be understood that should one of the heddles drop to the position illustrated in Figure 5, the bar will thereby be locked against longitudinal movement, and in such instance, the stop mechanism will be operated.

Referring now to the means for rocking the bar and for stopping the loom when the bar is locked, this consists of a bracket or 100 other suitable support 22, which may be secured to the loom frame or other fixed ele- 105

ment, as by means of outstanding ears 23 (Figure 1). The bracket has mounted therein a series of vertically extending levers 24 fulcrumed about a horizontal shaft 25 and 5 normally maintained in the position illustrated by full lines in Figure 2, by means of a series of springs 26. It will be understood that there is a lever for each detector bar, and any number of levers may be positioned within the bracket 22, corresponding 10 to the number of detector bars, the entire construction being very compact and readily variable as to the number of levers, due to the fact that they are all arranged within 15 a single bracket. One face 27 of each lever is tapered or inclined to co-operate with the end of a detector bar, the latter carrying a roller 29 adapted to ride over the face 27 of the lever as the heddle frame is lowered.

20 In the normal operation of the device, the levers 24 will be held in the position illustrated in Figure 2, and as the heddle frames descend, the detector bar will be moved longitudinally, through its engagement with 25 the lever, and as it moves longitudinally will be rocked or rotated, due to the provision of the spiral groove 20 and co-operating fingers 21. However, should one of the bars be locked, the corresponding lever will 30 be pressed inwardly as the roller 29 passes the horizontal plane of the fulcrum shaft 25, and render operative mechanism effective to stop the loom. The positions to which the lever 24 is moved by a locked detector bar is 35 illustrated in dotted lines in Figure 2. To maintain the lever in this position, detent or stop means is provided in the form of a series of independent detents 30, pivotally mounted above each lever upon a shaft 31, 40 and having shoulders 32, which drop behind any lever, the upper end of which is moved outwardly, due to inward pressure by a locked detector bar upon the portion of the lever below the fulcrum shaft 25, by a 45 locked detector bar. Thus any lever which is actuated by a locked bar is retained in the position to which it is moved thereby until the loom is stopped.

50 The mechanism rendered operative to stop the loom, through operation of one of the levers 24, may take any suitable form, but in the present instance, it preferably comprises a rod 33 pivotally supported at its ends for bodily swinging movement by 55 means of upwardly extending links 34, these being fixedly secured to a rotatable shaft 35. As will be understood, when the lower end of any one of the levers 24 is pressed inwardly, it engages the bar 34, and through 60 the rod 33 rotates the shaft 35. This shaft carries arm 36, which is connected by means of a pitman or link 37 with a forked lever 38. The lever 38 is pivotally mounted upon a pin 39 in a bracket 40, the bracket 40 being 65 fixedly secured to a longitudinally movable

bar 41, mounted in the loom frame (not shown), and having a hooked end 42 engaging the shipper lever S. The forked lever 38 is normally lowered (Figure 1), and in this position, it is out of the path of a dagger or pin 43 upon the loom lay L. As will be understood, the position of the lever 38, illustrated in Figure 1, is that in which it is normally maintained when the levers 24, engageable by the ends of the detector bars, are in their normal positions and the bars are free to be rocked thereby. Should one of the levers 24 be actuated by a locked detector bar, it will serve, through the mechanism described, to raise the lever 38 into the path of the dagger 43, and it will be maintained in this position by one of the detents 30 engaging the lever 24, which has been moved by the detector bar. As soon as the dagger engages the lever 43, the shipper lever will be actuated to stop the loom.

70 It is thought that the operation of this mechanism will be entirely clear from the foregoing description. It should, of course, be understood that numerous variations may be made in the structure illustrated and described without departing from the invention which is defined in the following claims.

75 I claim:—

1. In a warp stop motion for looms, the combination with a heddle frame and a series of heddles adapted to be supported therein by the warp threads, of a rockable longitudinally movable bar mounted in the heddle frame, the heddles having the bar associated therewith and being adapted to engage and lock the bar against movement when one of the warp threads breaks, means on the loom separate from the bar adapted to rock and longitudinally move the bar as the heddle frame moves, and power actuated means to stop the loom, said stop means being maintained inoperative as long as the bar is free to move under the influence of said actuating means.

80 2. In a warp stop motion for looms, the combination with a heddle frame and a series of heddles adapted to be supported therein by the warp threads, of a rockable longitudinally movable bar mounted in the heddle frame, the heddles having the bar associated therewith and being adapted to engage and lock the bar against movement when one of the warp threads breaks, means on the loom separate from the bar adapted to rock and longitudinally move the bar as the heddle frame moves, and power actuated means 85 separate from the heddle frame to stop the loom, said stop means being maintained inoperative as long as the bar is free to move under the influence of said actuating means.

90 3. In a warp stop motion for looms, the combination with a heddle frame and heddles supported therein by the warp threads,

95

- of a bar mounted in the heddle frame and free for rocking and longitudinal movement, the heddles having the bar associated therewith and being adapted to engage and lock the bar against rocking movement when one of the warp threads breaks, means on the loom separate from the bar adapted to move the bar longitudinally as the heddle frame moves, means to rock said bar as it is moved longitudinally, and power actuated means to stop the loom, said stop means being maintained inoperative as long as the bar is free to move.
4. In a warp stop motion for looms, the combination with a heddle frame and heddles supported therein by the warp threads, of a bar mounted in the heddle frame and free for rocking and longitudinal movement, the heddles having the bar associated therewith and being adapted to engage and lock the bar against rocking movement when one of the warp threads breaks, means on the loom separate from the bar adapted to move the bar longitudinally as the heddle frame moves, means on the heddle frame to rock said bar as it is moved longitudinally, and power actuated means to stop the loom, said stop means being maintained inoperative as long as the bar is free to move.
5. In a warp stop motion for looms, the combination with a heddle frame and heddles supported therein by the warp threads, of a bar mounted in the heddle frame and free for rocking and longitudinal movement, the heddles having the bar associated therewith and being adapted to engage and lock the bar against rocking movement when one of the warp threads breaks, means on the loom separate from the bar adapted to move the bar longitudinally as the heddle frame moves, cooperating means on the heddle frame and bar to rock said bar as it is moved longitudinally, and power actuated means to stop the loom, said stop means being maintained inoperative as long as the bar is free to move.
6. In a warp stop motion for looms, the combination with a heddle frame and heddles supported therein by the warp threads, of a bar mounted in the heddle frame and free for rocking and longitudinal movement, the heddles having the bar associated therewith and being adapted to engage and lock the bar against rocking movement when one of the warp threads breaks, means on the loom separate from the bar adapted to move the bar longitudinally as the heddle frame moves, means on the heddle frame to rock said bar as it is moved longitudinally, and power actuated means actuatable independently of the movement of the heddle frame to stop the loom, said stop means being maintained inoperative as long as the bar is free to move.
7. In a warp stop motion for looms, the combination with a heddle frame having a series of heddles supported by warp threads and a rockable bar mounted in the heddle frame and associated with the heddles, the heddles being formed to engage and lock the bar against movement when one of the warp threads breaks, of means on the loom adapted to rock the bar as the heddle frame moves, said means comprising a bracket, a substantially vertically extending lever mounted in said bracket about a horizontal axis at a right angle to the axis of said bar and yieldingly held against movement, said lever being pivoted at an intermediate point along the same and movable by the bar when the latter is locked as the heddle frame moves, but serving to move said bar when the latter is unlocked, and a member on the end of said bar adapted to be carried back and forth across the axis of said lever and along its two arms as the heddle frame moves.
8. In a warp stop motion for looms, the combination with a heddle frame having a series of heddles supported by warp threads, of a rockable and longitudinally movable bar mounted in the heddle frame and associated with the heddles, the heddles being formed to engage and lock the bar against movement when one of the warp threads breaks, means on the loom separate from the bar adapted to rock the same as the heddle frame moves, said means comprising a bracket, a member pivotally mounted about a horizontal axis on said bracket but yieldingly held against movement, said member serving normally to move the bar longitudinally as the heddle frame moves but being actuatable by the bar when locked to stop the loom, and means for rocking said bar as it is moved longitudinally by said member.
9. In a warp stop motion for looms, the combination with a heddle frame and a series of heddles adapted to be supported therein by warp threads, of a detector bar mounted in the heddle frame and being free for longitudinal movement, and means for rocking said bar as it is moved longitudinally, said heddles being formed to lock the bar against movement when one of the warp threads breaks.
10. In a warp stop motion for looms, a heddle frame having a series of heddles adapted to be supported therein by warp threads, a detector bar associated with the heddles, means for moving said bar longitudinally and simultaneously rotating the same, the heddles being adapted to lock the bar against movement when one of the warp threads breaks, and power actuated means to stop the loom operative only when said bar is locked against movement by a fallen heddle.
11. In a warp stop motion for looms, the combination with a plurality of heddle frames, each having a series of heddles sup-

ported by warp threads and a movable detector bar mounted in the heddle frame associated with each heddle, the heddles being formed to lock the bar against movement 5 when one of the warp threads breaks, of means on the loom frame adapted to be engaged by a locked bar as the heddle frames move to stop the loom, said means comprising a bracket, a plurality of substantially 10 vertically disposed levers independently mounted side by side in said bracket and each being movable about a substantially horizontal axis, said levers being pivoted at an intermediate point along the same and each 15 being engageable to actuate the bar when the bar is free for movement, a member operable by any one of said levers when actuated by a locked detector bar, means associated with said member adapted to stop the loom only 20 when said member is actuated by one of said levers, and an element at the end of each of said detector bars adapted to engage one of said levers, and to be carried along the two arms thereof as the heddle frame moves. 25 12. In a warp stop motion for looms, the combination with a plurality of heddle frames each having a series of heddles supported by warp threads and a rockable bar 30 yieldingly restrained against longitudinal movement mounted in said frame, and associated with said heddles, the heddles being formed to lock the bar against movement when one of the warp threads breaks, of means on the loom separate from the bars 35 adapted to rock the bars as the heddle frames move and to be actuated by a locked bar to stop the loom, said means comprising a bracket mounted on the loom frame, a plurality of levers pivotally and independently mounted 40 about a horizontal axis in said bracket and arranged side by side, said levers having a normal position in a common vertical plane, normal position in a common vertical plane, spring means for yieldingly retaining the le-

vers in said position, detent means for limiting the movement of said levers under the influence of said spring means, a rod engageable by any one of said levers, a continuously moving element on the loom, and means connected with said rod adapted to be moved thereby into the path of said continuously moving element only when the rod is actuated by one of said levers. 45 50 55

13. In a warp stop motion for looms, the combination with a plurality of heddle frames each having a series of heddles supported by warp threads and a rockable bar yieldingly restrained against longitudinal movement mounted in said frame and associated with said heddles, the heddles being formed to lock the bar against movement when one of the warp threads breaks, of means on the loom separate from the bars adapted to rock the bars as the heddle frames move, and to be actuated by a locked bar to stop the loom, said means comprising a bracket mounted on the loom frame, a plurality of levers pivotally mounted about a horizontal axis in said bracket and arranged side by side, said levers having a normal position in a common plane, spring means for yieldingly retaining the levers in said position, detent means for limiting the movement of said levers under the influence of said spring means, a rod engageable by any one of said levers, a continuously moving element on the loom, and means connected with said rod adapted to be moved thereby into the path of said continuously moving element only when the rod is actuated by one of said levers, said means comprising a 60 65 70 75 80 85

In testimony whereof I have hereunto set my hand.

HARRY E. KHOURY.
